UNITED STATES PATENT OFFICE.

BENJAMIN H. ANIBAL, OF HIGHLAND PARK, MICHIGAN, ASSIGNOR TO GENERAL MOTORS CORPORATION, OF DETROIT, MICHIGAN, A CORPORATION OF DELAWARE.

DESIGN FOR A FACE-PLATE FOR COMBINATION INDICATING INSTRUMENTS FOR MOTOR-DRIVEN VEHICLES.

58,530.

Specification for Design.

Patented Aug. 2, 1921.

Application filed April 7, 1921. Serial No. 459,477. Term of patent 14 years.

To all whom it may concern:

Be it known that I, BENJAMIN H. ANIBAL, a citizen of the United States, residing at Highland Park, county of Wayne, State of Michigan, have invented a new, original, and ornamental Design for a Face-Plate for Combination Indicating Instruments for Motor-Driven Vehicles, of which the following is a specification, reference being had to the accompanying drawing, forming part thereof.

The drawing shows my design for a face plate for combination indicating instruments for motor driven vehicles in front elevation.

I claim:

The ornamental design for a face plate for combination indicating instruments for motor driven vehicles illustrated in the accompanying drawing.

BENJAMIN H. ANIBAL.
